(57) **CLAIM**

The ornamental design for a self service terminal as shown and described.

DESCRIPTION

FIG. 1 is a top-left-front perspective view of a self service terminal showing my new design.

FIG. 2 is a front view of the self service terminal of FIG. 1. FIG. 3 is a back view of the self service terminal of FIG. 1. FIG. 4 is a left side view of the self service terminal of FIG. 1.

FIG. 5 is a right side view of the self service terminal of FIG. 1.

FIG. 6 is a top view of the self service terminal of FIG. 1. FIG. 7 is a bottom view of the self service terminal of FIG. 1; and,

FIG. 8 is a top-right-front perspective view of the self service terminal of FIG. 1.

The broken lines showing the repeating ovals towards the top of the self service terminal in FIGS. 1, 2 and 8 depict unclaimed environment only and form no part of the claim. All other broken lines in the drawings depict portions of the self service terminal that form no part of the claimed design.

1 Claim, 8 Drawing Sheets
